UNITED STATES PATENT OFFICE.

JOHN DOWNS, OF SAN FRANCISCO, CALIFORNIA.

SEWER-GATE.

SPECIFICATION forming part of Letters Patent No. 468,985, dated February 16, 1892.

Application filed October 9, 1891. Serial No. 408,255. (No model.)

To all whom it may concern:

Be it known that I, JOHN DOWNS, a citizen of the United States, residing in the city and county of San Francisco, State of California, 5 have invented an Improvement in Sewer-Gates; and I hereby declare the following to be a full, clear, and exact description of the same.

My invention relates to the class of doors 10 or gates for sewers for the purpose of preventing the backflow of tide or other water which may accumulate in the sewer and also to prevent sewer-gas passing from the main sewers into side sewers or house connections.

15 My invention consists in the peculiarly-constructed gate or door hereinafter fully described, and specifically pointed out in the claims, and its novel location with respect to the sewer and its connections.

20 The object of my invention is to provide a simple and effective gate or door of this class especially adapted for side sewer, and which will prevent the backwater from getting into said side sewers and will also answer for a trap 25 prevent the sewer-gas from passing into and through said sewers into buildings or street-openings which convey surface water into the sewers.

Referring to the accompanying drawings 30 for a more complete explanation of my invention, Figure 1 is a perspective view of my gate or door. Fig. 2 is a vertical section of same. Fig. 3 is a section showing it in place in a sewer.

35 The door or gate is made of an open-centered ring or frame A and a flap B, hinged to the frame A. These parts are preferably made of brass in order to resist the injurious action of salt-water and acids in the sewers, 40 though they may be made of other material. The frame A is a ring-shaped piece formed with an inner flange a, an outer flange a', and an intervening ridge a''. The frame is also provided with lugs or brackets a'', and the 45 flap B is provided with corresponding lugs or brackets b, and through said brackets a'' and b a pintle C passes, whereby the flap B is suspended from and is hinged to the frame A. The diameter of the flap B is such that it 50 laps well over and fits snugly against the inner flange a of the frame A and lies just

within the ridge a'', thereby forming a close joint. The ridge a'' at its lower portion is cut out or omitted, as shown at a'', which is for the purpose of preventing the accumulation of 55 dirt or other substances at that point, which would have a tendency to prevent the flap from closing tight. The frame A has also a top flange a'' extending inwardly at right angles. The flap B may have a bottom weight-lug b' to insure its closing. The door or gate is located in the sewer as follows:

D is one piece of sewer-pipe, and E is the adjacent piece, the latter being made of greater diameter than the former in order to 65 provide free and unobstructed space for the working of the flap. These two pipes fit together by the usual slip-joint; but the pipe D has its end flange d made thicker than usual to provide a firm bearing-surface for the frame 70 A, and the socket e of the pipe E is made deeper than usual to receive the flange d.

The frame A of the door or gate is fitted to the face of the end flange d of pipe D, with its top flange a'' fitting over the top portion 75 of said flange, and the frame is secured to the pipe by means of any usual cement, such as mortar or white or red lead. When the two pipes are fitted together, the outer flange a' of the frame fits and is confined snugly between the meeting faces of the joint of the two pipes, and suitable cement intervening holds the frame well in place. The faces of the two pipes are made upon a slight angle, so that the flap B in a closed position does 80 not quite reach the perpendicular, thereby providing for the firm closing by gravity of the flap against its seat in the frame A. The flap B works freely into the larger pipe E, so that it can not be obstructed. This pipe E, 85 as shown in Fig. 3, is the one which immediately joins the main sewer F. The pipes D and E therefore form part of the side sewer, and the pipe E may properly be termed the "protector" for the gate or door, because it 90 provides for the location of said gate or door outside of the main sewer, thereby preventing any contact of obstructing substances with it tending to disarrange it, as would be the case if it were located immediately within 95 the main sewer; also, pipe E being larger, the water has an increased force of flow as it 100

drops from pipe D, and this prevents dirt and rubbish from keeping the door from closing tight.

Having thus described my invention, what I claim as new, and desire to secure by Letters Patent, is—

1. A sewer gate or door consisting of an open-centered frame formed with an inner flange, an outer flange adapted to be confined between the meeting faces of adjacent pipes, and an intervening ridge, said ridge being cut away or omitted at its lower portion, and a flap hinged to the frame above and bearing against the inner flange thereof within the ridge, substantially as herein described. 15

2. A sewer gate or door consisting of an open-centered frame formed with an inner flange, an outer flange adapted to be confined between adjacent pipes, an intervening ridge, and with an upper flange a^5 , adapted to fit over the top of the end of the sewer-pipe, and a flap hinged to said frame and bearing against its inner flange within the ridge, substantially as herein described. 20

3. In combination with adjacent pipes of a sewer fitting together by a flange and socket, a gate or door having an outer flange a' , adapted to be confined between the meeting faces of said pipes and provided with a ridge a^2 , and a flap hinged to said frame and adapted to work freely in one of said pipes to open and close the opening in the gate, said flap adapted to lie within the ridge to form a close joint, substantially as herein described. 30

4. In combination with adjacent pipes of a sewer fitted together by a flange-and-socket joint, the plane of which is inclined from the vertical, a gate having open center and inner and outer flanges with intervening ridge, and a flap hinged to the frame and adapted to be seated within the ridge to close the opening in the gate and make a tight joint, substantially as herein described. 40

5. The pipes D and E of a sewer, said pipe E being greater in diameter than the pipe D 45 and the two pipes fitting together by a flange-and-socket joint, in combination with the open-centered frame A, having an outer flange a' fitting between the meeting faces of the joint of the pipes, an inner flange a , and an intervening ridge a^2 , and the flap B, hinged to the upper portion of said frame and adapted to bear against the inner flange a thereof, said flap operating freely in the larger pipe E, substantially as herein described. 50

6. The pipe D and the larger pipe E, fitting together by a flange-and-socket joint, in combination with the open-centered frame A, having a top flange a^5 , fitting over the top of the flange of pipe D, an outer flange a' , confined between the meeting surfaces of the joint of said pipes, an inner flange a , an intervening ridge a^2 , and the flap B, hinged to said frame and bearing against the inner flange a within the ridge a^2 , substantially as 65 herein described.

7. The main sewer, the pipe D of the side sewer, and the pipe E, larger in diameter than the pipe D and forming the connection between the side sewer and the main sewer, in combination with the open-centered frame A, confined between the meeting surfaces of the joint of the pipes D and E and provided with a ridge contiguous to the walls of the opening, and the flap B, hinged to said frame and operating within the pipe E to open and close said frame and adapted to lie within the ridge to form a close joint, substantially as 75 herein described.

In witness whereof I have hereunto set my hand.

JOHN DOWNS.
